UNITED STATES PATENT OFFICE.

HENRY M. HART AND JACOB L. SHOOK, OF NEW BRIGHTON, PENNSYLVANIA.

DESIGN FOR A NUT.

SPECIFICATION forming part of Design No. 33,198, dated September 11, 1900.

Application filed August 1, 1900. Serial No. 25,594. Term of patent 14 years.

all whom it may concern:

Be it known that we, HENRY M. HART and JACOB L. SHOOK, citizens of the United States of America, residing at New Brighton, in the county of Beaver and State of Pennsylvania, have invented and produced a certain new and original Design for Nuts, of which the following is a specification, reference being had therein to the accompanying drawings.

o This invention relates to a certain new and novel design in nuts, of which the following is a specification, reference being had to the accompanying drawings, forming a part thereof.

5 Figure 1 is a perspective view of the nut, showing our new design. Fig. 2 is a side view thereof.

As shown in the drawings, the leading or material feature of our design consists of a segment-shaped offset 1 on the outer face of the nut, the upper faces 2 of which are upon a plane parallel to the axis of the centrally-screw-threaded opening 3 in the segment-shaped end 4. The segment-shaped offset

has a concave recess 5, the face of which is substantially upon a plane with the threaded opening 3, the two side walls 6 of the segment-shaped offset being at an incline, converging toward each other, while the front wall or outer face of the same has an offset 7 at its lower end. Depending from the segment-shaped offset 1 is a block 8, the outer face of which is at an incline of a greater pitch than the underneath face and the rear face of which is curved at its junction with the segment-shaped offset 1.

Having thus described our invention, what we claim as new, and desire to secure by Letters Patent, is—

The design for a nut, substantially as herein shown and described.

In testimony whereof we affix our signatures in the presence of two witnesses.

HENRY M. HART.
JACOB L. SHOOK.
